FURMAN D. SPEAR, OF NEW YORK, N. Y., ASSIGNOR TO ARMSPEAR MANUFACTURING COMPANY, OF NEW YORK, N. Y., A CORPORATION OF NEW YORK.

SIGNAL-LANTERN.

1,274,098.

Specification of Letters Patent. Patented July 30, 1918.

Application filed February 10, 1917. Serial No. 147,798.

To all whom it may concern:

Be it known that I, FURMAN D. SPEAR, a citizen of the United States of America, residing at New York, N. Y., have invented a new and useful Signal-Lantern, of which the following is a specification.

My invention relates to an improved lantern construction which is particularly useful in connection with lanterns that are liable to be subjected to exposure, high winds, and jars. As an illustration of one use of a lantern wherein the light is maintained with the greatest difficulty, I may refer to a lantern suspended from a railway crossing gate arm, wherein it is common practice to suspend the lantern from the arm near its free end. When such gates are swung down to shut off the roadway they come to a sudden stop and the jar thus produced causes in many instances the snuffing out of the flame. By the use of my new construction it is practically impossible to so extinguish the flame. In other instances a quick upward impulse to the lantern tends to extinguish the flame. Here, again, by my improvement the flame is safeguarded.

I have shown my improvement as applied to a railway signal lantern, although it should be understood it is not necessarily limited in scope thereto.

In the drawings:

Figure 1 is a side elevation of the complete device on a small scale.

Fig. 2 is a vertical cross section on the plane of the line 2—2 of Fig. 3.

Fig. 3 is a cross section on the plane of the line 3—3 of Fig. 1.

Fig. 4 is a view of the underside of the lantern.

Fig. 5 is a perspective view of one of the details removed.

It should be understood that I have shown and shall describe herein in detail only one preferred form of my invention.

1 represents the main body of the lamp. The side of the lamp is suitably transparent. In this particular instance, I provide four light outlets covered by lenses 2—2. 3 represents the hood of the lantern, and 4 represents a well in the bottom of the main body. Within the well is mounted the lamp font 5 which is provided with a suitable burner 6 and wick raising and lowering device 7. 8 is a wall or partition mounted in

the well 4 between the side wall of the font 5 and the inside wall of said well 4. This wall is provided with a removable cap or cover plate 9 which has a central passage or vent for the burner of sufficient size to permit the burner to pass therethrough. I preferably provide around this burner opening a depending perforated annular wall 10, one function of which may be to bear down the burner when the cap 9 is in place to steady the burner and font and hold said parts in their operative position. Any suitable cones or deflectors may be provided in the upper part of the lamp, the particular construction being immaterial. In the particular form shown, however, 11 is an outlet cone. 12 is a cone located just below the outlet cone and supported by a body flange 13 and spaced therefrom by studs 14 to furnish an air passage. The edge of the cone 12 may overlap the flange 13 as shown, to effect a baffle plate action. In the upper part of the lamp body above the flange 13 I have shown a series of small air passages 15. In the lower part or well 4 I have shown other small air passages 16. 17 is a screen arranged between the wall 8 and the inner wall of the well 4 above the ports or passages 16, for the purpose of effecting a baffling action and to resist too strong currents of air through passages 16. The main oxygen supply for the flame is through the passage 15, or 16, or both. That is to say, the lamp may have both sets of air passages 15 and 16, or in some instances one or the other of said sets of openings may be omitted, depending upon the particular service for which the lamp is designed and it should therefore be understood that my invention does not relate to the particular means for furnishing the main oxygen supply. It will be observed that around the font 5 and burner 6 is an air chamber. 18—18 are ports which lead into the lower part of this air chamber, and 19—19 are ports in the cap 9 which lead into the upper part of said air chamber.

As shown in the drawings (see Figs. 3 and 4) the total area of the ports 19 which connect the interior of the cushioning chamber with the flame chamber is in excess of the total area of the ports 18 which connect the interior of the cushioning chamber with atmosphere, thus the total volume of air contained within the cushioning cham-

- ber furnishes a cushioning effect in the region of the flame in the event of any shock on the lantern, since the ports 18 offer greater resistance to the passage of air 5 into or out of the cushioning chamber than do the ports 19. Thus, it will be seen that the air around the font and base of the burner is not confined, but is merely restrained. This restraining of air around the base of 10 the burner provides in this vicinity a flexible air cushion or buffer, and since there are suitable ports leading into said chamber it follows that any shock up or down on the main air supply within the lantern around 15 the flame will be cushioned so that the flame will not be extinguished. By this improvement the lantern may be subjected to very severe blows and shocks both up and down without extinguishing the flame.
- 20 The lantern may be opened in any desired way. In this particular instance one of the lenses 2 is mounted in a hinged ring 20 so that the lantern may be opened at that side to afford access to the interior. To fill the 25 font, the lantern body is opened in the aforesaid manner, the cap 9 is then removed and the font lifted out and withdrawn through the opening covered by the lens 2 mounted in hinged ring 20.
- 30 I have not described at length the various details of construction which this lantern is shown to contain in common to other lanterns, since my invention is not limited to such features but relates more particularly 35 to the means which provides an elastic air cushion or buffer around and below the burner. This means may of course be modified in a variety of ways without departing from the spirit or scope of the invention and 40 the following claims. The number, shape, location and size of the vents into the air cushioning chamber and the method of forming the same may of course be varied to suit different conditions, it being essential, however, that such a chamber shall have one or 45 more vents leading to its lower part as well as to its upper part, and that the construction of such vents shall be proper to produce the desired cushioning effect.
- 50 What I claim is:
1. In a lantern, a body portion having an air admission port for normally supplying air to support combustion, an oil font and burner within said casing, a partition forming an air cushioning chamber around said burner and below the upper part thereof, a vent from said chamber to the interior of the lamp body and a vent from said chamber to the atmosphere, the latter vent being 55 more restricted than the former.
  2. In a lantern, a body having a flame chamber therein, said body having a port for normally supplying air to support combustion, a well adjacent to the bottom of 60 said body having a removable cover, an oil
- font and a burner located in said well, said cover having a passage for said burner, said well and cover forming an air cushioning chamber around said burner, a vent from said air chamber into said flame chamber, 70 and a vent from said air chamber to atmosphere, the latter vent being more restricted than the former.
3. In a lantern, a lantern body having a flame chamber therein, and having an air 75 admission port for normally supplying air to support combustion, an annular well at the bottom of said body, a removable cover for said well, said well and cover and the bottom of said lamp body forming an air cushioning chamber, an oil font having a burner mounted in said air chamber, said cover having a passage for said burner, one or more perforations in said cover to put said air chamber into communication with said flame 80 chamber and one or more perforations in the bottom of the lamp within said annular wall to put said chamber into communication with atmosphere, the latter vent being more restricted than the former. 90
4. In a lantern, a lantern body having a flame chamber therein, and having an air admission port for normally supplying air to support combustion, an annular wall in the bottom of said body, a removable cover for 95 said wall, said wall and cover and the bottom of said lamp body forming an air cushioning chamber, an oil font having a burner mounted in said air chamber, said cover having a passage for said burner, one or more perforations in said cover to put said air chamber into communication with said flame chamber and one or more perforations in the bottom of the lamp within said annular wall to put said chamber into communication 100 with atmosphere, the latter perforations being more restricted than the former, with means between said cover and said font and burner whereby said cover when in position 105 will operate to hold said font and burner in 110 position.
5. In a lantern, a body portion having an air admission port for normally supplying air to support combustion, a partition forming an air cushioning chamber in the 115 lower part of said body portion, an oil font within said chamber, a burner carried by said font, a burner passage and a vent in the upper part of said partition leading into the space within the lamp body, and a vent from 120 said chamber to the atmosphere, the area of the first mentioned vent being greater than the area of the last mentioned vent.
6. In a lantern, a lantern body, an oil font therein, a burner carried thereby, a 125 partition around said font forming an air cushioning chamber with air communicating passages leading from said chamber into the interior of the lamp and also to atmosphere, said passages being constructed to afford 130

- freer communication between said cushioning chamber and the interior of the lamp than between said cushioning chamber and the atmosphere.
- 5 7. In a lantern, a lantern body, an oil font therein, a burner carried thereby, a partition around said font forming an air cushioning chamber with air communicating passages leading from said chamber into the
- 10 interior of the lamp and also to atmosphere, said passages being constructed to afford freer communication between said cushioning chamber and the interior of the lamp than between said cushioning chamber and
- 15 the atmosphere, with air ports in the wall of the lamp body outside of the cushioning
- chamber for supplying air to support combustion independently of the first mentioned perforations.
8. In a lantern, a body having a flame 20 chamber therein, said body having a port for normally supplying air to support combustion, a well adjacent to the bottom of said body having a cover, an oil font and a burner located in said well, said cover having a passage for said burner, said well and cover forming an air chamber around said burner, a vent from said air chamber into said flame chamber, and a vent from said air chamber to atmosphere, the first mentioned vent being freer than the other. 25
